Application April 14, 1954, Serial No. 29,995

Term of patent 7 years

(Cl. D34—15)

To all whom it may concern:

Be it known that I, Audrey A. Namowitz, a citizen of the United States of America, residing at Bronx, in the county of Bronx and State of New York, have invented a new, original, and ornamental Design for a Toy House for Children, of which the following is a specification, reference being had to the accompanying drawing, forming part thereof.

In the drawing:

Fig. 1 is a front perspective view of a toy house for children, showing my new design with the front door ajar;

Fig. 2 is a rear perspective view thereof, to a reduced scale;

Fig. 3 is a cross-sectional view thereof, to a reduced scale, taken on line 3—3 in Fig. 1 but showing both front and rear doors partially open; and

Fig. 4 is a cross-sectional view thereof, to a reduced scale, taken on line 4—4 in Fig. 1 but showing both the front and rear doors closed.

I claim:

The ornamental design for a toy house for children, as shown.
